UNITED STATES PATENT OFFICE.

CLEVELAND A. DUNN, OF NEW YORK, N. Y., ASSIGNOR TO GRAFF, WASH-
BOURNE & DUNN, OF NEW YORK, N. Y., A CORPORATION OF NEW YORK.

DESIGN FOR A TEETHING-RING.

SPECIFICATION forming part of Design No. 36,283, dated April 14, 1903.

Application filed October 24, 1902, Serial No. 128,671. Term of patent 7 years.

To all whom it may concern:

Be it known that I, CLEVELAND A. DUNN, of New York, county of New York, State of New York, have invented and produced a certain new, original, and ornamental Design for a Teething-Ring, fully described and illustrated in the following specification and the accompanying drawings, forming a part of the same.

10 The object of the present invention is to provide a new, original, and ornamental design for a teething-ring; and the essential feature of the design consists of the representation on the ring of a flower and a precious

15 stone, with a space for a suitable word or legend, as illustrated in the accompanying drawings, showing, in—

Figure 1, a face view of the ring, and in Fig. 2 an edge view, and in which the ring A has the birth-stone *a*, the birth-flower *b*, and the space *c* for the name of the month or other suitable word or legend.

What I claim is—

The ornamental design for a teething-ring, substantially as shown and described. 25

In testimony whereof I have hereunto set my hand in the presence of two subscribing witnesses.

CLEVELAND A. DUNN.
